UNITED STATES PATENT OFFICE

101,649

DESIGN FOR AN AWNING FRAME OR SIMILAR ARTICLE

Clyde Reynolds, Chicago, and Bohumil G. Kucera,
Cicero, Ill., assignors of one-half to Joseph M.
Zalusky, Cicero, Ill.

Application April 23, 1936, Serial No. 62,262

Term of patent 14 years

To all whom it may concern:

Be it known that Clyde Reynolds, a citizen of the United States, and residing in the city of Chicago, in the county of Cook and State of Illinois, and Bohumil G. Kucera, a citizen of the United States and residing in the town of Cicero, in the county of Cook and State of Illinois, have invented a new, original, and ornamental Design for an Awning Frame or Similar Article, of which the following is the specification, reference being had to the accompanying drawing forming a part thereof.

On the drawing:

Fig. 1 is a perspective view of an awning frame showing our new design.

Fig. 2 is a side elevational view thereof.

We claim:

The ornamental design for an awning frame or similar article, as shown.

CLYDE REYNOLDS.
BOHUMIL G. KUCERA.
